UNITED STATES PATENT OFFICE.

EMMETT S. WEBSTER, OF SOUTH BEND, AND JOHN W. BELLAIRS, OF MISHAWAKA,
INDIANA.

LOOM.

1,331,603.

Specification of Letters Patent.

Patented Feb. 24, 1920.

Application filed June 4, 1919. Serial No. 301,736.

To all whom it may concern:

Be it known that we, EMMETT S. WEBSTER and JOHN W. BELLAIRS, citizens of the United States, residing, respectively, at 5 South Bend and Mishawaka, in the county of St. Joseph and State of Indiana, have invented certain new and useful Improvements in Looms, of which the following is a specification.

10 Our invention relates to an improvement in looms, and more particularly to a hand operated loom adapted for teaching the art of weaving.

The object of the invention resides in the 15 provision of a loom which is simple in structure, adapted throughout for manual operation and adjustment and constructed with the view to enable the pupil to readily understand the proper manipulation of the parts 20 in the weaving process, and to conveniently control the various operations to produce the character of the weave or the design desired. A further object resides in the provision of finger operated means for rapidly 25 manipulating the heddle frames and holding same in elevated position. A still further object resides in the provision of a plurality of spools for the warp threads mounted on a common shaft for simultaneous rotation 30 under the influence of the shaft movement, and means whereby certain of the spools may be adjusted with relation to the shaft to bring slack threads to the proper tension, so that the tension of all the warp threads 35 will be maintained substantially uniform.

With the above and other objects in view, the invention in the preferred form of details will be described in the following specification, reference being had particularly to 40 the accompanying drawings, in which:

Figure 1 is a side elevation of the improved loom.

Fig. 2 is a front elevation thereof.

Fig. 3 is a top or plan view thereof.

45 Fig. 4 is a fragmentary view of the spool shaft showing the manner of mounting and locking the spools to the shaft.

Fig. 5 is a section taken on the line 5—5 of Fig. 4, showing the means for adjustably 50 locking the spools to the shaft.

The improved loom comprises a main frame 6, having end uprights 7 connected by side bars 8, and upper and lower cross-bars 9 and 10, respectively, connecting the 55 upper and lower ends of the uprights 7.

Mounted upon the frame is a harness frame 11, consisting of the uprights 12, and cross beams 13 secured to the upper opposite edges thereof, which construction provides an open upper end for the harness frame. Suitably 60 secured to the main frame and projecting laterally thereof in line with the harness frame is a shelf 14, upon which are mounted fixed inverted L-shaped hook members 15 arranged in spaced order and in step forma- 65 tion as shown.

Mounted in the harness frame 11 is the harness, comprising in this instance four independent heddle frames 16, provided with the customary heddles 17, through the eyes 70 of which (not shown) the warp threads 18 are passed, all in the manner and for the purpose well understood in the art. Fulcrumed upon the harness frame 11, as by means of a pivot bolt 19, are levers 20, one 75 for each heddle frame, and connected at their inner ends to the upper ends of the heddle frames by link bars 21, which points of connection, as at 22 and 23, are effected by suitable pivot members to permit relative 80 angular movement between the levers and the links. The said levers project through slots 24 in one of the harness frame uprights, and their free ends terminate short one with relation to the other, and which ends piv- 85 otally support depending L-shaped latch keys 25. Said latch keys provide a finger hold for depressing the levers, and in the act of depressing the same may be swung so as to catch beneath the hook members 15 90 for maintaining the heddle frames so operated in elevated position. A slight outward push on the latch keys with the finger will release the same from the hooks, and it will thus be apparent that the operator 95 may acquire great skill in the rapid manipulation of the latch keys to operate the heddle frames in the order desired. By having the levers 20 of different lengths at their outer ends, the latch keys thereon are thus dis- 100 posed in spaced relation viewed from the front end of the loom, as shown in Fig. 2, thus permitting a particular one to be readily operated without interference. The heddle frames are maintained in their inoperative or lowered position by coil springs 26 terminally secured to the bottom of the frame, and secured at 27 to the main frame. 105

Mounted at one end of the main frame is a cloth roll 28, the shaft 29 of which is pro- 110

vided with a crank handle 30, and a ratchet wheel 31 engaged by a pawl 32 to prevent accidental unwinding of the cloth from the roll. By a winding action of the cloth roll 5 the warp threads are also brought to the desired tension. Suitably journaled at the opposite end of the main frame is a shaft 33, having a crank handle 34, a ratchet wheel 35, and a pawl 36, which pawl and 10 ratchet are arranged to hold the shaft against rotation in the winding up movement of the cloth roll. Mounted upon the shaft 33 are a plurality of warp spools 37, having pivotally mounted thereon, as at 39, 15 a pair of relatively different length pawls 40. The pawls of the two outer spools at the opposite ends of the shaft are adapted to engage between teeth formed by an annular row of serrations 41 in the shaft, and 20 the pawls of the intermediate spools are adapted to engage a longitudinal groove 42 cut in the shaft. Each of the pawls is spring pressed, as indicated at 42', and are adapted to independently lock each spool 25 to the shaft so that they will all turn in unison, while at the same time the spools may be rotatively adjusted with relation to each other. The object of this is to permit any slack occurring in any of the warp 30 threads to be taken up, so that all of the threads may be maintained under substantially uniform tension. In the act of shifting the hand shuttle 43, upon which the woof thread is wound, back and forth through the shed, the novice is apt to apply 35 undue weight upon the warp threads by accidentally striking the same with the hands or with the shuttle in the manipulation of the latter, thereby causing the threads so affected to stretch. The marginal threads, as carried by the two end spools at each end of the spool shaft, are 40 generally so affected, and by the double pawl arrangement described the slightest slack in the threads may be taken up, so as 45 to maintain all of the threads under substantially uniform tension.

The improved loom is designed primarily for school room use to teach the children 50 the art and science of weaving, and its essential characteristics are the means for maintaining a proper and uniform tension upon the warp threads, and the particular means for operating and locking the heddle 55 frames in operative position.

While the foregoing is the preferred form of our invention, we desire it to be understood that we do not limit ourselves to the

precise structure shown and described, as it is obvious that the same may be variously 60 modified without departing from the spirit of the invention.

What is claimed is:—

1. A hand loom involving a main frame, a harness frame mounted thereon, a plurality of heddle frames arranged for vertical movement in the harness frame, a series of levers for independently operating the heddle frames, and means carried by the free ends of said levers for locking the same in 70 lowered position.

2. A hand loom involving a main frame, a harness frame mounted thereon, a plurality of heddle frames arranged for vertical movement in the harness frame, a series 75 of levers for independently operating the heddle frames, and means for locking the free ends of the levers in lowered position, said means in part constituting finger keys for depressing the levers to raise the heddle 80 frames.

3. A hand loom involving a main frame, a harness frame mounted thereon, a plurality of heddle frames arranged for vertical movement in the harness frame, a series of 85 levers pivoted on the harness frame for independently operating the heddle frames, links pivotally connected with one end of said levers and the heddle frames, finger keys pivoted to the outer terminals of said 90 levers, a bracket supported by and extending to one side of the main frame, and hooks mounted on said bracket adapted for engagement by the finger keys for locking the levers in lowered position.

4. A hand loom involving a main frame, a harness frame mounted thereon, a plurality of heddle frames arranged for vertical movement in the harness frame, a series of levers for independently operating the heddle frames, and elements carried by the levers adapted for both manipulating and locking the same in operative position.

5. A hand loom involving a main frame, a harness frame mounted thereon, a plurality of heddle frames arranged for vertical movement in the harness frame, a series of levers for independently operating the heddle frames, latch elements pivotally carried by the free ends of said levers, and means 105 cooperating with said elements for locking the levers in lowered position.

In testimony whereof we affix our signatures.

EMMETT S. WEBSTER
JOHN W. BELLAIRES.
